MACHINE FOR FORMING THE LOWER SEGMENT OF IN-PLACE CONCRETE PIPE

Oscar E. Jerner, Turlock, Calif.

Application February 27, 1950, Serial No. 146,522

9 Claims. (Cl. 61—63)

1

This invention relates in general to the formation of concrete pipe in-place in a pre-dug trench.

The primary object of the invention is to provide a novel machine for forming the lower segment of in-place concrete pipe; the machine being operative to form said lower segment as a continuous run.

Another object of the invention is to provide a machine, as above, which includes, in novel combination, a truck guided in the pre-dug trench, and a form for the lower segment of the pipe trailing the truck; the truck having a rigid, rearwardly projecting, longitudinal pipe beam, and the form being rockably mounted on the pipe-beam.

A further object of the invention is to arrange the rockable form in a manner such that an operator may stand at one point on the form and rock it about the pipe-beam whereby to work and smooth the concrete; the form being closed on top and the concrete being poured thereover into the trench as the machine advances.

An additional object of the invention is to provide the truck with novel gauge and guide wheels; there being a vertically adjustable gauge wheel running in the bottom of the pre-dug trench, and laterally adjustable guide wheels running on opposite sides of said trench.

A still further object of the invention is to provide a finishing form adapted to trail the rockable leading form; there being a novel connection between said forms.

It is also an object of the invention to provide a machine, for forming the lower segment of in-place pipe, which is designed for ease and economy of manufacture.

Still another object of the invention is to provide a practical and reliable machine for forming the lower segment of in-place concrete pipe, and yet one which will be exceedingly effective for the purpose for which it is designed.

These objects are accomplished by means of such structure and relative arrangement of parts as will fully appear by a perusal of the following specification and claims.

In the drawings:

Fig. 1 is a side elevation of the machine as in use.

Fig. 2 is a rear end elevation of the leading form which trails the truck.

Fig. 3 is a transverse section on line 3—3 of Fig. 1.

Fig. 4 is a fragmentary longitudinal section showing the trailing form and the manner of its connection to the leading form.

2

Fig. 5 is a sectional plan view of the truck showing primarily the mounting of the gauge and guide wheels.

Fig. 6 is a fragmentary side elevation of the truck's gauge wheel as fitted with a skid for use in a soft bottom trench.

Fig. 7 is a fragmentary front end elevation of the gauge wheel and skid, as in Fig. 6.

Referring now more particularly to the characters of reference on the drawings, the novel machine, for forming the lower segment of in-place concrete pipe, comprises a truck, indicated generally at 1, which truck has a rigid main frame 2 supported from below by a vertically adjustable gauge wheel 3. The gauge wheel 3 includes a spindle 4 which projects upwardly through a tubular mount 5, and such spindle is vertically adjustable by means which includes an adjustment crank 6 above said tubular mount 5. Steering of the gauge wheel 3 is accomplished by means of a knuckle arm 7 which projects laterally from the yoke or fork 8 which carries the gauge wheel 3, and a steering rod 9 extends upwardly and rearwardly from the knuckle arm 7, threading through a swivel nut 10 secured to an upstanding rear portion 11 of the main frame 2.

Rearwardly of said frame portion 11 the steering rod 9 is fitted with a crank 12. By manipulating the crank 12 the operator can readily set the direction of the gauge wheel 3.

A centrally disposed, longitudinal pipe-beam 13 projects rearwardly in rigid relation from the main frame 2 of the truck 1, and a boat-like form, indicated generally at 14, is mounted on the rearwardly projecting portion of the longitudinal pipe-beam 13 in draft relation to the truck 1. The construction and mounting of the boat-like form 14 will hereinafter appear in detail.

The truck 1 is adapted to be advanced forwardly in guided relation in a pre-dug trench 15 having a half-round bottom 16, in the following manner:

At the front thereof the main frame 2 supports a winch unit, indicated generally at 17, driven through the medium of an endless belt and pulley unit 18 from an engine 19 mounted on the rear portion of said frame 2. The endless belt and pulley unit 18 is normally slack, but is adapted to be brought into driving operation by a tightener 20 actuated by a link 21 from an upstanding, winch brake release lever 22. The winch brake release lever 22 is controlled by a rod 23 pivotally connected between the upper end of said lever 22 and a bellcrank lever 24 on

the upper end of the portion 11 of the frame. One leg of the bellcrank lever 24 is extended upwardly and rearwardly some distance as a hand lever 25.

By manipulating the hand lever 25 the winch brake lever 22 is swung to a winch release position and simultaneously the belt tightener 20 causes the endless belt and pulley unit 18 to impart a drive from the engine 19 to the winch 17. A cable 26 leads forwardly in the trench from the winch unit 17, and some distance ahead of the truck 1 such cable is anchored to a stake. In this manner the operator has selective control of advance of the machine, which advance is guided, in the trench, as follows:

The main frame 2 includes, at opposite sides, laterally adjustable side frames 27 of inwardly extending U-configuration, each such side frame 27 having telescopic legs 28 normally locked against relative movements by set screws 29.

Each side frame 27 is fitted, at its outer end, with a vertical-axis guide wheel 30 which is set to run on the adjacent side wall of the trench, thereby maintaining the truck guided for movement in said trench. The side frames 27 each carry guards 31 to the rear of the guide wheels 30.

The working height of the truck relative to the bottom of the trench is regulated by relative vertical adjustment of the gauge wheel 3 by 30 means of the adjustment crank 6.

Under conditions where the bottom of the trench is soft, the gauge wheel 3 seats in a skid 32 which is relatively wide and round-bottomed in matching relation to the half-round bottom 16 of the trench. See Figs. 6 and 7. The skid 32 not only prevents the gauge wheel 3 from digging into the bottom of the trench, but also tends to maintain its proper alignment in the trench.

The boat-like form 14 is shaped, in transverse section, symmetrical to the half-round bottom of the trench 16, but on a lesser radius whereby when the machine advances in the trench, the lower half of said form serves to shape the inner surface of the lower segment 33 of the formed in-place concrete pipe.

To the end that the boat-like form 14 be rockable about the rearwardly projecting pipe-beam 13, such form is formed, at opposite ends, with hubs 34 and 35 through which said pipe-beam turnably extends.

The pipe-beam 13 projects out of the rear end of the form 14, and a mounting collar 36 is secured on said projecting portion of the pipe-beam by a cross pin 37; the mounting collar 36 supporting, in fixed relation, an upstanding cross plate 38.

This cross plate 38 is formed, on opposite sides, with laterally projecting trowels 39 whose lower troweling edges 40 are adapted to smooth the upper edges of the half-round lower segment of the formed in-place concrete pipe.

Additionally, the cross plate 38 carries, at opposite ends, upstanding, rearwardly projecting side wings 41 which work into the lower segment of the formed pipe adjacent the upper edges, serving to stabilize and smooth the adjacent wall of concrete directly rearwardly of the lower troweling edges 40.

The boat-like form 14 is fitted on top with a hood 42 which is exteriorly convex transversely of said form, and at the rear end of the latter the hood 42 is fitted with transversely spaced foot platforms 43.

Another boat-like form 44, likewise half-round

in bottom configuration, and substantially matching the transverse section of the leading form 14, trails the latter.

At its rear end the leading form 14 is fitted 5 with a pair of transversely spaced, rearwardly projecting, longitudinal shafts 45 which extend in slidable relation through corresponding bosses 46 on the front end of the trailing form 44; there being tension springs 47 connecting between the 10 adjacent ends of said forms 14 and 44 directly above the shafts 45 whereby to yieldably maintain the form 44 in trailing relation to the form 14.

When the above described machine is in operation 15 it is placed in the pre-dug trench 15, with the forms 14 and 44 initially set upon a prelaid base of fresh concrete so as to establish the initial level. Thereafter, with slow advance of the machine by the truck, in the manner previously described, fresh concrete is poured over 20 the front portion of the hood 43, spilling downwardly about the form 14 and filling the entire space between the lower half of the same and the half-round bottom 16 of the trench.

The operator stands with his feet on the foot platforms 43 so that he can readily rock the form 14 about the pipebeam 13 as an axis, so as to assist in shaping and smoothing of the concrete which is being formed—upon advance of the machine—into the lower segment 33 of the in-place concrete pipe.

As the foot platforms 43 are at the rear of the form 14, the fresh concrete can be poured over the hood ahead of the operator, yet by merely leaning forward the operator has full access to, and control of, the hand lever 25 and crank 12.

To prevent the fresh concrete, as it is being poured, from splashing into the apparatus on the main frame 2, the upstanding rear portion 40 of said frame carries a splash shield 48.

As the machine advances, the form 14 effectively shapes the lower segment 33, the upper edges of said segment being troweled by the lower edges 40 of the trowels 39, and the lower portions of the rearwardly projecting side wings 41 smoothing the adjacent wall surfaces of the concrete.

While the leading form 14 effectively shapes the lower segment 33, the trailing form 44 imparts a final finish to the inner wall surface thereof; such trailing form 44 rocking with the leading form 14 by reason of the described connection therebetween.

The machine is highly effective to form the lower segment 33 of in-place concrete pipe, with the operation a continuous one; the machine being readily one-man controlled.

After the lower segment of an in-place concrete pipe is formed, in the bottom portion of a pre-dug trench, with the present machine, another machine follows and forms the upper segment of the pipe; such other machine being the subject of co-pending application, Serial No. 146,521, filed February 27, 1950, now Patent No. 2,574,213.

From the foregoing description it will be readily seen that there has been produced such a device as substantially fulfills the object of the invention, as set forth herein.

While this specification sets forth in detail the present and preferred construction of the device, still in practice such deviations from such detail may be resorted to as do not form a departure from the spirit of the invention, as defined by the appended claims.

Having thus described the invention, the fol-

lowing is claimed as new and useful, and upon which Letters Patent are desired:

1. A machine for forming the lower segment of in-place concrete pipe in a pre-dug trench, comprising a truck adapted to travel in the trench ahead of the concrete, a longitudinal centrally disposed beam projecting rearwardly from and rigid with the truck, a boat-like form rearwardly of the truck, and means mounting the form on the beam for transverse rocking thereabout as an axis.

2. A machine for forming the lower segment of in-place concrete pipe in a pre-dug trench, comprising a truck adapted to travel in the trench, a longitudinal beam projecting rearwardly from and rigid with the truck, a boat-like form rearwardly of the truck, the beam projecting through the form, means mounting the form on the beam for transverse rocking about the latter as an axis, a member fixed on the beam rearwardly of the form, and trowels on opposite sides of said member positioned to work the corresponding upper edges of said segment.

3. A machine for forming the lower segment of in-place concrete pipe in a pre-dug trench, comprising a truck adapted to travel in the trench, a longitudinal beam projecting rearwardly from and rigid with the truck, a boat-like form rearwardly of the truck, the beam projecting through the form, means mounting the form on the beam for transverse rocking about the latter as an axis, a member fixed on the beam rearwardly of the form, trowels on opposite sides of said member positioned to work the upper edges of the segment, and upstanding rearwardly projecting side wings mounted on said member adjacent the trowels positioned to work the inner face of said segment adjacent said edges.

4. A machine for forming the lower segment of in-place concrete pipe in a pre-dug trench, comprising a truck adapted to travel in the trench ahead of the concrete, a longitudinal centrally disposed beam projecting rearwardly from and rigid with the truck, a boat-like form rearwardly of the truck, means mounting the form on the beam for transverse rocking thereabout as an axis, and transversely spaced foot platforms on the form adjacent the top thereof.

5. A machine for forming the lower segment of in-place concrete pipe in a pre-dug trench, comprising a power-operated truck adapted to travel in the trench, a longitudinal beam projecting rearwardly from and rigid with the truck, a boat-like form rearwardly of the truck, means mounting the form on the beam for transverse rocking thereabout as an axis, and transversely spaced foot platforms on the form adjacent the top thereof; the truck including control members

manually accessible to an operator standing on said platforms.

6. A machine for forming the lower segment of in-place concrete pipe in a pre-dug trench, comprising a truck adapted to travel in the trench, a boat-like round bottomed form rearwardly of the truck, means connecting the form in trailing relation to the truck and for transverse rocking about a longitudinal axis, and platform means on the form arranged whereby an operator standing on said platform means may so rock said form; there being another boat-like form trailing said first named form, and means connecting the trailing form to said first named form in draft relation and for transverse rocking thereby.

7. A structure, as in claim 6, in which said last named connecting means comprises, a pair of transversely spaced longitudinal shafts extending between adjacent ends of the forms, the shafts being fixed to the end of one form and slidably guided through the adjacent end of the other form, and longitudinally yieldable tie means between said adjacent ends of the forms.

8. A machine for forming the lower segment of in-place concrete pipe in a pre-dug trench, comprising a truck adapted to travel in the trench, a boat-like form rearwardly of the truck to ride on the concrete, and means connecting the form in trailing relation to the truck for vertical movement of the truck and form as a rigid unit; the latter including a front end vertically adjustable gauge and supporting member adapted to run on the bottom of the trench ahead of the concrete.

9. A machine for forming the lower segment of in-place concrete pipe in a pre-dug trench, comprising a truck adapted to travel in the trench, a boat-like form rearwardly of the truck, and means connecting the form in trailing relation to the truck; the latter including a steerable gauge wheel adapted to run on the bottom of the trench, a removable skid adapted to receive said gauge wheel, said skid being relatively wide and substantially symmetrical to the cross section of the bottom portion of the trench, and means to locate the skid on the wheel so that the skid may be steered with the wheel as a unit.
